UNITED STATES PATENT OFFICE.

MAHLON S. STRAUSE, OF READING, PENNSYLVANIA, ASSIGNOR TO SCHUYLKILL SILK MILLS, OF READING, PENNSYLVANIA, A CORPORATION OF PENNSYLVANIA.

UNION-SUIT.

1,251,439.

Specification of Letters Patent. Patented Dec. 25, 1917.

Application filed May 26, 1917. Serial No. 171,162.

To all whom it may concern:

Be it known that I, MAHLON S. STRAUSE, a citizen of the United States, residing at Reading, in the county of Berks and State of Pennsylvania, have invented certain new and useful Improvements in Union-Suits; and I do hereby declare the following to be a full, clear, and exact description of the invention, such as will enable others skilled in the art to which it appertains to make and use the same.

This invention relates to garments, and more particularly to union suit under-garments.

It is an object of this invention to improve the construction of this type of garment so as to secure what might be called a closed crotch structure.

With these and other objects in view the invention consists of the construction, the combination, and in details as more fully hereinafter described and shown in the accompanying drawing in which:

Figure 1 is a front elevation of the garment.

Fig. 2 is a rear elevation.

Fig. 3 shows a fragment with the parts spread to clearly show the construction.

Fig. 4 is a sectional detail.

Fig. 5 is a plan of the front pattern indicating one front flap, in dotted lines, as applied.

Fig. 6 is a plan of one of the front flaps.

Fig. 7 is a plan of a rear left side rear pattern, and

Fig. 8 is a plan of a rear seat reinforce.

The garment may be constructed of variously designed patterns and therefore it will be understood that the herewith illustrated and described elements are employed for the purpose of exposition of the invention, which latter may be incorporated as most convenient and desirable, to secure the provision of a closed split crotch.

With this in view a front pattern is shown, in Fig. 5, of one piece 2 having limb elements 3-3 divergent on lines 4-4 from the medial line along which the front piece

is slit at 5. To each edge of slit 5 is secured at 7 a flap piece 6, Fig. 6, thus forming a lateral portion to overlap as in Fig. 1.

The rear of the garment may comprise right and left pieces, one of which is shown at 8, Fig. 7, having a limb portion 9. To obtain a closed crotch each back piece 7 is provided with a lateral flap portion 10 extending from the upper inner seam line 11 upward to a suitable distance. These front and rear sections 2 and 8 are then stitched respectively at 4 to 11, and with their side edges 12-13 together and along the back members at 14 down to the top of flap 10. The front and rear flaps 6 and 10 of respective limbs of the garment are stitched at 15, and, therefore, in the completed garment, the flap of one side extends from point *a*, Fig. 1, down, thence across the crotch at *b* and up the back at *c*, Fig. 2. One continuous flap becomes the inner element while the other becomes the outer, as clearly shown in Figs. 3 and 4. The front and rear limb elements may be fully reinforced by crotch pieces 16, Fig. 8.

What is claimed as new is:

A union suit having a front member the legs of which diverge from the crotch point, the trunk being split on a medial line upwardly from the crotch apex toward the waist line; overlapping flap pieces attached each to a respective side of said split and terminating at the crotch apex with a transverse edge, and a pair of back pieces stitched together on a medial line from neck to waist and from crotch to knee to the legs of the front, each back piece having a lateral portion to one side of the medial line of the back, terminating at the crotch and having a transverse edge stitched at the crotch to the respective edge of a flap on the front member, the united front and rear flaps respectively telescoping together and forming a closure for the front and back of the opening and beneath the pelvic bone.

In testimony whereof I affix my signature.

MAHLON S. STRAUSE.
